UNITED STATES PATENT OFFICE.

RICHARD STAR, OF BROOKLYN, NEW YORK.

SHIP'S LOG.

Application filed June 29, 1926. Serial No. 119,502.

This invention relates to ship's logs and has for an object to provide an improved construction wherein there is presented a minimum number of moving parts while a substantially accurate reading is secured at all times and at different speeds.

Another object of the invention is to provide an improved actuator structure wherein the power transmitting cable is connected by 10 a single lever with the actuating piston.

A further object, more specifically, is to provide in a ship's log actuator a lever structure and means for moving the same with the parts so arranged that packing is eliminated while the effective length of the lever 15 may be varied as desired.

In the accompanying drawings—

Figure 1 is an elevation with certain parts in section showing a complete ship's log including the indicator and actuator.

Figure 2 is a vertical sectional view through the Pitot tube and associated parts shown in Figure 1.

Figure 3 is a longitudinal vertical sectional view through the actuator shown in Figure 1.

Figure 4 is an end view of the actuator shown in Figure 3.

Referring to the accompanying drawings by numerals, 1 indicates the bottom of a ship on which the device is mounted. As indicated in Figure 1, an aperture 2 is formed in the bottom 1 and connected with the bottom 1 in any suitable manner is a valve 3 which covers aperture 2. Valve 3 is of special construction and is provided with a bore 4 sufficiently large to permit the Pitot tube 5 to extend therethrough and still leave a space for the passage of water to the pipe 6. Whenever the Pitot tube 5 is removed, the handle 7 is rotated and the valve 3 is closed. The tube 6 may be flexible if desired, though ordinarily it is an ordinary pipe used on ships and at the end opposite that associated with valve 3 it is connected to the bottom of an actuating cylinder 8. A pipe 9 leads from near the top of the actuating cylinder 8 and is connected to the Pitot tube 5 through a flexible connection 10. As indicated in Figure 3, the actuator cylinder 8 is divided into a lower compartment 11 and an upper compartment 12 by the piston 13 and the diaphragm 14. A suitable valve 15 is connected

to the upper end of cylinder 8 so as to exhaust chamber 12 of air and a valve 16 is connected to the bottom of cylinder 8 to exhaust chamber 11 of air. The inner end of the valve 16 is connected to a flexible pipe 17 which has its opposite end connected by a suitable fastening device 18 to the piston 13 whereby all of the air in the cylinder including that confined in piston 13 may be exhausted when water is permitted to flow through pipe 6 into chamber 11. When water flows into chamber 12 the air is exhausted out of valve 15. As soon as water begins to 65 pass out of these valves, the workman will then close the valves and the device is then in operative condition. Before chamber 11 completely fills, the casing 19 carrying lever 20 is filled with water and also the pipe 21 70 is filled with water up to the water level exteriorly of the ship. Pipe 21, casing 19 and chamber 11 are all supplied with water under the usual hydrostatic head produced by the depth at which these devices are placed. The 75 chamber 12 is also filled in the same manner but when the ship begins to move forwardly, the Pitot tube which faces forwardly will begin to function and additional water will be forced into chamber 12 under pressure. 80 This additional water will begin to move piston 13 downwardly and thereby expel some of the water from chamber 11. The amount of downward movement of the piston 13 varies with the amount of pressure exerted thereon by the incoming water which is in proportion to the speed of the ship. As both sides of the piston 13 are under pressure equal to the hydrostatic head of water, a slight increase of pressure in chamber 12 85 will produce a movement of the piston 13 in proportion to this additional pressure. This results in causing the instrument to be very sensitive and also very accurate at low speeds as well as high speeds.

The casing 19 is preferably rectangular, though it could be round or any desired shape as the same merely is an enclosure for receiving the lever 20 which is connected at one end with the cable or rod 22. This cable 100 or rod extends upwardly and sometimes over pulleys until it reaches the indicator 23. The indicator 23 may be of any approved kind, as for instance, that shown in one of my

prior applications. Cable 22 is connected with indicator 23 in such a manner that as this cable pulls or moves downwardly it will cause the indicator to function and when the cable is released, the indicator will automatically move back to its former position and pull the cable back with it. The lever 20 at the end opposite table 22 is loosely mounted on a bearing edge 24 carried by the bearing block 25. A pin 26 acts to keep the lever 20 in engagement with the bearing edge 20 whereby a proper pivotal action is secured at all times. A threaded aperture is provided in the block 25, said aperture receiving the threaded section 26 of an adjusting rod 27.

From Figure 3 it will be noted that this rod extends through a suitable packing gland 29 which is preferably kept rather tight so that the rod 27 will be frictionally held against movement in either direction and also against accidental rotation, though the same may be rotated by a proper instrument, as for instance, a large screw driver. The packing gland 29 is threaded exteriorly for receiving a protecting cap 30 which is screwed over the end of rod 27 and over the gland whereby these parts cannot be accidentally injured or tampered with. By adjusting the bearing block 25 back and forth, the effective length of lever 20 is changed, and, consequently, a different degree of pull given to a lever for a specified movement of piston 13. A piston rod 31 is connected to piston 13 and extends through a connection 32 in which it loosely fits. The lower end 33 of rod 31 is preferably arc-shaped for fitting on the arc-shaped bearing portion 34 of lever 20 whereby a proper contact will be secured as the lever is swung upwardly and downwardly. It will be noted that the actuator shown in Figures 3 and 4 consists of the actuator cylinder 8, casing 19 and associated parts. This structure is provided with one movable packing, namely, the diaphragm 14.

What I claim is:

1. In a ship's log an actuator adapted to be actuated by the pressure of water, said actuator including a casing, a tube extending upwardly from the casing and in free communication with the interior thereof, a power transmitting cable positioned in said tube, a lever arranged in said casing connected at one end with said cable, a fulcrum for the opposite end of said lever, means for shifting said fulcrum for varying the effective length of said lever, a member for operating the lever in one direction, a piston for operating said member, a tube for directing water from the bottom of the ship to one side of said piston, a Pitot tube for directing water against the opposite side of said piston whereby the pressure of water on the piston will be greater on one

side than on the other when the ship is moving forwardly.

2. In a ship's log an actuator comprising a casing, a lever pivotally mounted in the casing, a power cylinder, a piston arranged in said power cylinder, a piston rod connected with said piston and extending from the power cylinder into the casing and into operative engagement with the lever for moving the lever when the piston is moved in one direction, means for directing water to one side of said piston, and Pitot tube means for directing water to the other side of said piston whereby, when the ship is in motion, more pressure will be produced on said other side than on said first side and said piston and the lever will be moved in proportion to the speed of the ship.

3. In a ship's log an actuator including a power cylinder, a casing in free communication therewith, a piston arranged in the power cylinder, a diaphragm carried by the piston and connected at one point to the cylinder for dividing the cylinder into an upper and lower chamber, means for directing water under pressure to said lower chamber, said lower chamber supplying water to said casing whereby said lower chamber and casing are filled with water under pressure, Pitot tube means for supplying water to the upper chamber whereby pressure in said upper chamber will be greater than in said lower chamber when the ship carrying the device is in motion, said pressure acting to move the piston in one direction, a power lever arranged in said casing, and a piston rod connecting said piston with the power lever whereby the movement of the piston will be communicated to the lever.

4. In a ship's log an actuator including in its construction a casing, a tube extending upwardly from the casing for accommodating a pull cable, a lever pivotally mounted in said casing and connected at one end with said cable, said lever being formed with a bearing, a rod resting on said bearing for actuating said lever, a piston for actuating said rod, a cylinder for said piston, a tube connecting the lower part of said cylinder with the bottom of the ship carrying the actuator, said tube being in free communication with the water exteriorly of the ship and a Pitot tube for directing water from a point exteriorly of the bottom of the ship to the upper part of said cylinder whereby said piston will be moved in proportion to the movement of the ship on which the device is mounted.

5. In a ship's log an actuator including in its construction a casing, a power cylinder in free communication with the casing, a lever arranged in the casing, a piston arranged in the power cylinder and substantially dividing the same into upper and lower compartments, a piston rod connected

with said piston and extending into the casing, said piston being operatively connected with said lever for actuating the lever in one direction, and a pair of pipes for directing the water from the bottom of the ship carrying the actuator to opposite ends of said cylinder respectively, one pipe having the

lower part functioning as a Pitot tube whereby when the ship is in motion the piston will be moved in proportion to the speed of the ship and said lever will be actuated also in proportion to the speed of the ship. 10

RICHARD STAR.
